UNITED STATES PATENT OFFICE.

WILLIAM FRANCIS GANNON, OF PARKMAN, WYOMING.

TOOL.

1,303,788.

Specification of Letters Patent. Patented May 13, 1919.

Application filed June 18, 1918. Serial No. 240,572.

To all whom it may concern:

Be it known that I, WILLIAM F. GANNON, a citizen of the United States, and a resident of Parkman, in the county of Sheridan and 5 State of Wyoming, have invented certain new and useful Improvements in Tools, of which the following is a specification.

My invention is an improvement in tools, and has for its object to provide a tool 10 especially designed for use in building and repairing wire fences.

In the drawings:

Figure 1 is a top plan view of the improved tool in use;

15 Fig. 2 is a similar view of the tool enlarged;

Fig. 3 is a front view;

Fig. 4 is a section on the line 4—4 of 20 Fig. 1.

In the present embodiment of the invention the improved tool comprises two handle members 1 and 2 pivotally connected, the member 1 having a reduced portion 3 which is received between lugs 4 on the portion 2, 25 and the lugs and the reduced portion are connected by a rivet 5.

Beyond the pivotal connection the handle member 1 has a fork 6, and between the fork and the reduced portion 3 this member has 30 lateral enlargements 7. The member 2 has similar enlargements 8, and each pair of enlargements 7 and 8 coöperate to form two pairs of gripping jaws. The jaws 9 and 10 of the handle members 1 and 2, respectively, 35 are adjacent to the reduced portion, and these have plane faces which grip the wire tightly when clamped upon the same.

The jaws 11 and 12, which are at the outer sides of the jaws 9 and 10, are recessed, as 40 shown, to receive the wire, to permit the wire to turn and to slip. The handle member 2 has notches 13 and 14 at the end adjacent to the pivotal connection, but spaced apart therefrom, and the abutting surfaces of the 45 handle members 1 and 2 adjacent to the pivotal connection are grooved or corrugated, as indicated at 15, to coöperate as gripping jaws.

A wire cutter is formed at the pivotal connection, by notches 16 and 17 in the reduced 50 portion of the member 1 and in the lugs 4, respectively.

In use, to patch a broken wire, for instance, the operator will go back on each 55 side of the break as far as the wire is slack. The tool will be opened and the wire will be

gripped between the jaws 9 and 10, and the tool will be placed with the claw against a post, as shown in Fig. 1, on that side of the post toward the break. The grip portions 60 of the handle members are now pulled toward the break, and the powerful leverage obtained will stretch the wire tightly up to that point. A staple may now be placed, and the tool may be moved to the next point. 65

With a slack wire of, say, five hundred yards, with the usual tools it would be necessary to loosen the wire on fifty or sixty posts and stretch from the corners. With the present tool, however, two or three times in 70 this distance is ample for the stretching. After the wire has been tightened up to the break on both sides an extra piece of wire of about eighteen inches in length is fastened to one end of the broken wire. The 75 other end of the broken wire is placed between the jaws 11 and 12, with about six inches of the wire extending through on that side of the tool which is uppermost. This is bent back and hooked in the notch 13. 80 The tool is now held in line with the wire, with the claw end toward the break. That end of the wire having the extra piece is now picked up and drawn over the top of the tool, pulling the wire as taut as possible by 85 hand. This extra wire is now hooked in the notch 14, and the tool is brought gradually to a vertical position and the extra wire is engaged with the claw.

The tool is further turned until it is reversed, when the wire is stretched perfectly, with one strand crossing the other between the apex of the claw, and the jaws 9 and 11 on the under side of the tool. The tool is 90 now turned around horizontally, and the 95 wires are bent across each other just back of the claw. The tool is now opened, thereby opening jaws 11 and 12 and releasing the wire; then the loose ends of the wire are wrapped around the body of the wire clear 100 of the loop. The other end of the wire is taken out of the notch and is wrapped in the same manner. The jaws 11 and 12 hold the wire loosely and permit the wire to turn and to slip, so that there is no danger of breaking 105 the same.

I claim:

1. A tool of the character specified, comprising a pair of handle members pivoted together at one end, one of the members having 110 a longitudinally extending claw at the said end and each of said members having at

its opposite sides lateral extensions coöperating to form gripping jaws at each side of the tool, those portions of the jaws near the free ends of the extensions being recessed on 5 their inner faces to grip a wire and to permit the wire to slip and to turn in the recesses, that handle member not provided with the claw having notches beyond the pivotal connection from the claw for engagement by the wire.

2. A tool of the character specified, comprising a pair of handle members pivotally connected at one end, one of said members

having a claw extension beyond the pivotal connection, and both of the said members 15 having a pair of coöperating jaws at each side thereof, the outermost jaws having rounded recesses for receiving the wire to permit the wire to turn and slip, that handle member not having the claw being provided 20 with notches for the purpose specified.

WILLIAM FRANCIS GANNON.
